TRUCK FOR THE STORAGE AND TRANSPORT OF FOLDING CHAIRS AND OTHER ARTICLES

James Lister Skinner, Memphis, Tenn., assignor to American Seating Company, Grand Rapids, Mich., a corporation of New Jersey

Application December 31, 1956, Serial No. 44,363

Term of patent 14 years

(Cl. D14—3)

The figure is a perspective view of a truck for the storage and transport of folding chairs and other articles, showing my new design.

I claim:

The ornamental design for a truck for the storage and transport of folding chairs and other articles, substantially as shown.
